ELECTRIC SWITCH

Chester I. Hall, Rexford, and Alexander W. Bedford, Schenectady, N. Y., assignors to General Electric Company, a corporation of New York

Application July 25, 1942, Serial No. 452,262

5 Claims. (Cl. 200—92)

Our invention relates to electric switches, more particularly to alternating current electric switches of the type known as contactors, and has for its object a simple and low cost electric switch, a switch which without the use of auxiliary arc extinguishing apparatus opens electric circuits carrying high currents at substantial voltages with no appreciable arcing between the contacts and, moreover, an electric switch whose operating parts and operation are unaffected by extremely heavy shocks or blows applied to the support on which the switch is mounted.

In conventional contactors such as used in the starting and the control of electric motors, the movable contact is operated by an electromagnet which when energized moves the movable contact into engagement with the stationary contact at a very high speed with destructive hammer blow effect between the contacts.

These contactors are opened by deenergization of the magnet or the release of a latch, and the movable contact moves to its open position at a very high speed and the contacts are widely separated so that a long arc is established between them. This long arc supplies a relatively large amount of heat and is consequently difficult to cool and extinguish. Consequently, it may re-establish itself each half cycle and persist for a number of cycles. The opening of such contactors under substantial current and voltage conditions is accomplished by violent electric explosive effects and considerable noise produced by this arcing between the contacts. Another disadvantage of conventional electromagnetically operated contactors is that they may be opened or closed by shocks or jars applied to the panel or support on which the contactor is mounted.

We have found that in the opening of electric circuits carrying substantial alternating currents at substantial voltages, such as the circuits of alternating current electric motors up to 100 H. P. or more at voltages of 440 or more, there is an optimum range of speed of movement of the movable contact with respect to the stationary contact within which the arcing between the contacts and destructiveness of this arcing is a minimum. This speed range at commercial frequencies of 60 cycles and voltages up to 600 is between the limits of .25 to 4 inches a second, although we prefer a speed within the limits of .5 to 1.5 inches a second. At contact speeds either lower or higher than this range, the destructiveness of the arc increases rapidly with decrease or increase in the contact speed.

In this optimum range of speed, the contacts

have time to be separated a small distance only before the alternating current passes through the zero point of its voltage wave. This is true even when the separation of the contacts begins soon after the zero point is passed and the contacts therefore continue to separate throughout substantially the entire half of the voltage wave up to the next zero point. In such case, arcing between the slightly separated contacts occurs but 5 does no appreciable damage to the contacts because of the rapid cooling of the arc by the close proximity of the contact surfaces. Thus current is conducted across such a very short gap with no detrimental effect. Also, such a short arc is a 10 low energy arc and generates a relatively small amount of heat. When the zero point in the voltage wave is reached, however, the arc is extinguished because of lack of voltage and the separation of the contacts is then great enough to 15 prevent reestablishment of the arc as the voltage increases.

We have found that in a 550-volt, 60-cycle motor circuit a separation of the contacts of only two mils (.002") is sufficient to prevent reestablishment of the arc. This is because the permissible voltage per mil of gap for very small or 20 minute gaps is much higher than for relatively wide air gaps. Preferably, however, we continue the separation of the contacts to about .25 inch as 25 a precaution against unusual conditions such as the accumulation of dirt on the contacts. In carrying out our invention, we preferably move the movable contacts to their closed circuit positions into engagement with the stationary contacts by means of an electric motor connected to 30 drive the contacts at a suitable speed low enough to prevent hammer blows. This closing speed is high enough, however, to prevent any appreciable period of light pressure between the contacts, 35 such as would cause welding of the contacts together because of the high electrical contact resistance and high heat generation. For opening of the contacts, we provide a spring which is wound up during the closing movement and which 40 operates when the motor is deenergized to drive the motor backwards and open the contacts. The relation of the force applied by the spring to the inertia of the various parts driven by it is such 45 that the contacts are opened at a predetermined 50 optimum speed at which arcing is minimized.

Preferably also, we connect the motor to the movable contacts through a crank linkage which is on dead center when the contacts are either open or closed so that the operating mechanism 55 is not affected by shocks and, therefore, the

switch can not be either opened or closed by such shocks.

We also provide manually operated means for closing or opening the contacts independently of the driving mechanism.

For a more complete understanding of our invention, reference should be had to the accompanying drawings, Fig. 1 of which is an exploded fragmentary view in perspective of a switch embodying our invention; Figs. 2, 3 are fragmentary views showing details of construction; Fig. 4 is a bottom view of Fig. 3; Fig. 5 is a plan view of a complete switch embodying the features of Figs. 1 to 4, inclusive; Fig. 6 is a side elevation view partly in section of Fig. 5; Fig. 7 is a sectional view along the line 1—1 of Fig. 5 looking in the direction of the arrows; Fig. 8 is a sectional view along the line 8—8 of Fig. 5 looking in the direction of the arrows; while Fig. 9 is a sectional view showing details of construction.

Referring to Fig. 1 of the drawings, in one form of our invention the movable contacts of the switch are mounted on an operating or cross bar 10 made of electrically insulating material, such as a moulded compound, provided with a central cylindrical portion 11 to which is secured one end of an operating link 12. This link or operating rod 12 is pivotally connected at its other end to a crank constituted by a pin 13 secured to a gear 14 a suitable distance from the pivot axis support 15 for the gear. Thus rotation of the gear 14 moves the cylindrical portion 11 longitudinally and thereby moves the bar 10 between its closed and open circuit positions. Electric driving means shown as a rotary type electric motor 16 is connected to drive the gear 14 through a gear train comprising a gear 17 mounted on the shaft 18 of the motor, a large gear 19 meshing with the gear 17, a shaft 20 to gear 19 meshing with the gear 17, a shaft 20 to which the gear 19 is secured, and a small gear 21 secured on the shaft 20 and meshing with the gear 14.

Preferably, the motor 16 is operated electrically in one direction only, and preferably also as shown in the drawing, this rotation of the motor moves the bar 10 to its closed circuit position. When energized the motor turns the gear 14 through its gear train connection therewith to the position shown in the drawings in which the link 12 comes to rest against a flange 22 secured to the gear 14 whereby the gear 14 is stopped forcibly with the pin 13 in a dead center position with respect to the link 12.

As long as the switch is held closed the motor remains energized and holds the gear 14 in this position.

For opening movement of the switch bar 10 a spiral spring 23 is provided, constituting an energy storage device, the outside end of which is connected to a fixed post 24 and the inside end of which is connected to the shaft 20. This spiral spring is wound up by the clockwise rotation of the gear 19, looking down on Fig. 1, during the switch closing movement. Upon deenergization of the motor, the spring turns the gear 19 in a counterclockwise direction and thereby moves the gear train, the switch and the rotor of the motor to their open circuit positions. This open circuit position is again defined by the flange 22 which moves again into engagement with the link 12 although on the side of the link opposite that shown in Fig. 1 whereby the pin 13 is stopped in its opposite dead center position.

In order to effect the opening of the contacts at the predetermined desired slow speed with a

minimum of arcing, which we have found to be a speed between .25 and 4 inches a second and preferably between .5" and 1.5" a second, the spring 23 is constructed to apply an opening force sufficient to give this desired rate of contact opening movement. It will be observed that, by reason of the fact that the pin 13 is in its dead center position when the switch is closed, the contact holding force applied through the link 12 does not assist the spring at the beginning of the opening movement. As the pin 13 moves away from the dead center position, a component of the contact holding force tends to rotate the gear 14 toward the open position and therefore assists the spring 23. Preferably, separation of the contacts begins after about 70° movement of the gear 14 in a clockwise direction looking down on Fig. 1. At that time the spring has accelerated the gear and other driven parts to their maximum speeds. After 180° rotation of the gear, it is brought to rest, as previously stated, by engagement of the flange 22 with the link 12.

For the purpose of absorbing the kinetic energy of the motor rotor and other moving parts in both the closed and open positions after the driving parts have been brought to rest by engagement of the flange 22 with the link 12, a friction clutch connection is provided between the shaft of the motor and the gear 17. This clutch consists of a disc 25 (Fig. 2) secured to the gear 17, a disc 26 secured to the motor shaft 18 and a suitable loose friction disc 27 between them. The gear 17 is loose on the shaft 18 and is pressed by a spring 28 against the disc 25 whereby the gear is rotationally secured to the shaft by the friction between the discs. This friction is great enough to stop the rotor of the motor in one or two revolutions after the driving mechanism has come to rest. The friction should be as great as consistent with the strength of the parts driven by the motor in order to make available, in the event of welded contacts, as much as possible of the stored energy of the motor rotor.

As shown, the cross bar 10 carries four bridging contact members 29, 30, 31 and 32, although in the control of a 3-phase motor, for example, only three of these will be used. These bridging members are secured at approximately their centers to the arm 10. Each carries a movable contact at each end cooperating with suitable stationary contacts 33 and 34 which are connected to suitable terminals for connection in the circuit of the electric motor or other device to be controlled.

We have found that in order to prevent arcing in the event of a weld between the contacts, the bridging members 29 and 32 and the other operating parts for the bridging members must be stiff and unyielding so as to break the weld without appreciable bending or flexing. In other words, the parts must be sufficiently stiff and unyielding to separate the welded contacts at the predetermined low speed. It will be obvious, on the other hand, that if the bridging members and other driving parts were resilient in the breaking of a weld, the movable contact immediately upon the breaking of the weld would snap away and move at a very high speed until the operating parts recovered their normal shapes. Such rapid opening movement by reason of the spring recovery action of the parts would result in destructive arcing between the contacts. Preferably, the bridging members are channel members for the purpose of increasing their rigidity.

The contact pressure is determined by the

strength of a helical spring 35 (Fig. 6) mounted between each bridging member and the cross bar on the side of the bridging member opposite the movable contacts so as to be compressed during the final movement of the cross bar after engagement of the contacts. Each bridging member, as shown, extends through an aperture 36 provided for it in the cross bar. When the contacts are disengaged, the bridging member is held by the spring 35 on the seat for it formed by the lower or opposite wall of the aperture 36. During the opening movement of each bridging member, it is held in its closed circuit position by the spring 35 as the cross bar 10 moves away until the cross bar 10 is rigidly engaged by the bridging member. Then the bridging member is forcibly moved away from the stationary contacts.

By means of a knob 37 the cross bar 10, when in its open circuit position, can be latched in that position so that it can not be closed by the driving motor 16 or by shocks. Furthermore, when the cross bar is in its open circuit position, the knob 37 can be turned to release the cross bar from the link 12 and then the cross bar can be operated manually between its open and closed circuit positions and latched in its closed position as well as in its open position, as stated above, so that it can not be opened by the spring 23 or by shocks.

This knob 37 is secured to a sleeve 38 which is rotatably mounted in a longitudinal bore provided for it in the cylindrical member 11, the center line of the sleeve 38 being coincident with the center line of the link 12. The link 12 extends into the sleeve 38 and is provided with a pin 39 which extends into a slot 40 in the sleeve. At each end as shown the slot 40 has a short transverse portion extending circumferentially of the sleeve while the main portion of the slot extends lengthwise of the sleeve. Normally the pin 39 lies in the right-hand transverse portion, Fig. 1, as shown, whereby the driving rod 12 is rigidly connected to the cross bar 10.

On the end of the sleeve 38 opposite the knob 37 is a transversely extending flange member 41 having two diametrically opposite projections 42 and 43 extending outward beyond the periphery of the supporting portion 11. A spring 44 (Fig. 6) is provided in the knob which engages a hexagonal disc 45 secured to the end of the sleeve 38 thereby to bias the sleeve toward the left hand with respect to the knob, the disc 45 moving in a hexagonal seat in the knob, and hold the flange 41 and the knob against opposite sides of the cylindrical portion 11. Furthermore, the cylindrical portion 11 extends loosely into a bore 46 (Fig. 6) provided for it in the stationary support 47 made of electrically insulating material on which the stationary contacts are secured.

Ordinarily, the projections 42 and 43 are free to move axially during movement of the cross bar 10 in slots 48 and 49 (Fig. 3) provided for them in opposite sides of the bore 46. If it is desired manually to close the switch, the switch at the time being open, the knob 37 is turned in a clockwise direction, as seen in Fig. 1, so as to bring the axial slot 40 into register with the pin 39 and then the knob is pushed inward on the rod 12 carrying with it the contact bar 10 to the closed position which brings the pin 39 to the left-hand end of the slot 40, as seen in Fig. 1, or rather the sleeve 38 is pushed inward until the end wall of the slot engages the projection 39. If it is desired to lock the switch in this closed position, the knob 37 is now turned still

farther in a clockwise direction which is permitted by the outer lateral end portion of the slot 40 whereby the projections 42 and 43 move into the recesses 50 and 51 (Fig. 4) under the lower end of the wall of the bore 46 and latch the contact bar 10 in its closed circuit position. This manual closing operation compresses the helical spring 50a surrounding the link 12 and having one end bearing on the flange 41. After thus being closed manually, the switch can be opened manually by the reverse operation of the knob, the spring 50a pushing the knob and cross bar 10 to their open positions.

The contact bar 10 may be latched in the open position after it has been moved by the motor 16 to the open position, by turning the knob to its extreme counterclockwise position as permitted by the much longer circumferential transverse end portion 51a of the slot at the right-hand end of the slot 40, as seen in Fig. 1. This transverse portion of the slot 51a, together with the other transverse portion, provides for about 90 degrees total rotation of the sleeve 38 and knob 37. It will be seen that when the bar 10 has been moved to its open circuit position by the motor the lugs 42 and 43 are in position to be moved over the shoulders 52 and 53 simply by turning the knob 37 counterclockwise, whereby the contact bar is latched in its open position.

To facilitate the operation of the switch by the knob 37, the knob is provided with a peripheral dial flange on which suitable position marks numbered 1, 2, 3 and 4 are provided, these marks registering with a mark 53a on the cross bar. With the dial in position as shown in Figs. 1 and 5, i. e., the No. 2 mark registering with the stationary mark 53a, the cross bar is operated normally by the motor 16. To move the cross bar to its closed circuit position and lock it as just described, the dial is turned to the position No. 3, pushed in and then turned still farther clockwise to the position No. 4. Counterclockwise rotation of the knob from position No. 2 of Fig. 5 to position No. 1 latches the cross bar in its open circuit position as just described. Moreover, the knob may be latched in any of these positions by providing a projection (not shown) on the inner side of the knob at each position and corresponding depression for the projection in the cross bar 10.

The above described releasable connection means between the cross bar 10 and the link 12, and the latching means whereby the cross bar can be secured in either its open circuit or closed circuit position, form no part of our invention and are described and claimed in a co-pending application S. N. 455,458, filed on August 20, 1942, by Edgar H. Ayers, and assigned to the same assignee as this invention.

As shown, the motor 16 is preferably a split phase motor having a capacitor or condenser 54 connected permanently in parallel with one of the motor windings.

A second capacitor 55 is connected in the circuit of the motor for the purpose of reducing the voltage applied to the motor after the motor has closed the switch so that the motor can remain energized on the supply circuit without overheating for indefinite periods of time. This capacitor 55 is short-circuited when the switch is in its open circuit position by means of an interlock switch operated by the gear 14. As shown in Fig. 1, the spring contact arm 56 of this interlock switch normally engages a stationary spring contact 53a thereby to short-circuit the capacitor

55. When the gear 14 is turned to the closed switch position, as shown in Fig. 1, a projection 57 on the flange 22 engages a pin 57a made of electrically insulating material, the other end of which engages the end of the spring contact arm 56. As the gear 14 completes its final movement to the open position, the pin 57a is moved to push the spring contact arm 56 away from the stationary contact and thereby open the short circuit around the capacitor 55. The motor 16 may be constructed, for example, for 80-volt alternating current continuously applied, but it may be operated on a much higher voltage from the alternating current supply source 58, such as 440 volts, in the actual closing of the switch. This higher rate of voltage gives the motor a high rate of acceleration and the closing period of operation is so short that the motor is not overheated and damaged.

The operation of the switch arm 56 by the gear 14 assures that the short circuit around the capacitor 55 is opened only after the switch is closed and the motor 14 is nearly in its final closed position. At that time the pin 13 is closely approaching its dead center position shown in Fig. 1, and consequently the force applied to the gear by the operating rod 12 has only a very small component in opposition to the rotation of the gear by the motor. Thus the motor has enough torque under these conditions after the short circuit around the capacitor 55 is opened to complete the final closing movement of the gear 14. This arrangement avoids the possibility of the opening of the short circuit around the condenser under conditions such that the motor can not complete the closing movement. Such conditions might occur if the short-circuit switch were operated by the cross bar 10 and a permanent electric connection were used in place of the push button 59, and a condition were encountered of slowly rising voltage on the supply circuit. In such case, the motor might operate back and forth to open and close the short-circuit switch repeatedly with opening and closing of the main switch contacts carried by the bar 10.

When the capacitor 55 has been inserted in the motor circuit and the voltage of the motor thereby reduced, in the example shown to about 80 volts, the torque of the motor is enough to slightly more than overbalance the opening countertorque applied by the spring 23 to the shaft 20.

As shown, the motor circuit is closed by means of a normally open push button switch 59. This connects the motor directly to the supply source 58 through the normally closed stop push button 59a, push button 59 and the interlock switch contacts 56 and 56a which at this time are in engagement with each other. The closing button 59 is held closed until the switch has been moved to its closed circuit position after which the button 59 may be released and allowed to open because it is then short-circuited by the interlock switch arm 60 operated by the cross bar 10. To open the switch the normally closed push button 59a is opened to deenergize the motor after which the switch is opened by the spring 23.

The speed of the contacts carried by the bridging members 29 to 32 inclusive at the instant of closing, i. e., engagement with the stationary contacts, is higher than the contact opening speed and is high enough to prevent welding of the contacts together because of high electrical contact resistance between them. Thus if the

contacts are brought together at a very low relative speed, the high contact resistance between them caused by their low pressure of engagement may last long enough to cause welding of the contacts together. However, the closing speed is low enough to avoid destructive hammer blow action between the contacts.

It is contemplated that the device will be mounted in position on a panel or other support so that the bridging contact members 29 to 32 inclusive are substantially vertical. In this position it will be noted that each bridging member cooperates with a bottom stationary contact and a top stationary contact. The bar 10 is furthermore operated in such manner that during the opening movement the bridging members disengage their top stationary contacts first and thereafter disengage their bottom stationary contacts. This sequence avoids the possibility of the lower contacts separating first and generating ionized gas which would rise and envelope the top contacts at the time they open. This effect would be especially pronounced in the event of heavy overloads.

The required tilting of the cross bar 10 about its longitudinal center line to effect this sequence in the opening of the top and bottom contacts is effected by means of the mechanical crank driving connection for the cross bar. Thus the device disclosed is mounted in a position such that the stationary contacts 34 (Fig. 1) are uppermost with the bridging contact members extending substantially vertically. In this device, the gear 14 was rotated about 70 degrees by the spring 23 to effect a separation of the top bridging contacts from the stationary contacts 34. It will be observed that the pin 13 in moving through this 70-degree angle imparts an appreciable tilting action to the cross bar 10 through the operating connecting rod 12 because of the fact that the plane of rotary movement of the crank or gear 14 is substantially parallel with the planes of movement of the bridging contact members. In order to provide for this tilting of the cross bar, the bore 46 (Fig. 6) in the support 47 is made considerably larger at its right-hand end than the cylindrical portion 11 of the cross bar extending into it. After this separation of the upper contacts, continued rotation of the gear 14 separates the lower contacts.

During the opening movement the springs 35, which are compressed in the closed circuit position, apply a component of force through the bar 12 to the gear 14 in the same direction as the force applied by the opening spring 23. This component of force becomes available after a slight movement of the gear 14 from the dead center position. As the gear 14 turns, this component of force of the springs 35 increases, although this may be offset to a slight extent by the decreased pressure applied by the springs as they elongate. At the point of circuit opening, as previously stated, after the gear 14 has moved about 70 degrees, the gear 14 and other moving parts have been accelerated to a speed giving the desired optimum opening speed of the contacts. Of course, when the bridging contacts separate at one end from the stationary contacts, the force applied by the springs 35 to the rod 12 is materially decreased by reason of the fact that the cross bar has then been moved outward and tilted so that the edge at one end of each of the openings 36 engages a bridging contact. In other words, the bridging contacts become each seated at one end of its aperture 36. Thus

after the circuit is open, the spring 23 is practically the sole operating means for the gear 14 and other parts. Consequently, the gear 14 is accelerated to its maximum speed, as are also the other moving parts, before the contacts open and continues at that speed until the bridging contacts have been moved approximately to their full open circuit positions.

It will be observed that the engagement of the cross bar with the bridging contacts, the cross bar and other moving parts moving at their optimum speed, gives a hammer blow on the bridging contacts which is of value in the separation of the contacts in the event of a weld. The rotating parts, some of which, such as the rotor of the motor 16, rotate at quite high speeds, serve as energy inertia members or flywheel members and apply a powerful opening force to the cross bar.

Figs. 5 to 8, inclusive, show various additional structural details of an electric switch constructed as described in connection with Figs. 1 to 4, inclusive.

Referring to Figs. 5 and 6, the bridging contact members 29 to 32, inclusive, are shown as channel members whereby these members are made stiff enough to prevent their bending during the breaking of a weld between the contacts. With the switch in its closed circuit position, the bridging members as shown each have their ends resting on stationary contacts and the cross supporting bar 10 in moving still farther compresses the helical spring 35, Fig. 6, between the upper side of each bridging contact and the upper wall of the cross bar. These springs and the bridging contacts are held in position by a screw 61 extending through a hole in the cross bar and provided with a nut 62 which holds the screw or bolt in position and also forms a seat for the upper end of the spring 35. The screw has an unthreaded portion at its lower end which extends loosely through an aperture in the middle of the bridging contact member so as to hold the bridging contact member against lengthwise movement with respect to the cross bar.

Figs. 5 to 8, inclusive, show the construction of the supporting member 47 made of insulating material on which is carried the stationary contacts, and also the construction of the cross bar 10. It will be observed that the support 47 is provided with a series of electrically insulating barrier walls separating the bridging members and stationary contacts. Thus the bridging member 29 is between two walls 63 and 64 formed as part of the support 47. Each of these walls, as shown in Fig. 8, is provided with a central notch 65 to receive the cross bar 10. The cross bar likewise has arc walls 66 and 67 (Fig. 5) on opposite sides of the bridging contact 29 and overlapping, respectively, the slots or notches in the walls 63 and 64.

This electrically insulating support 47 has secured to it a rectangular metal wall 68 which forms a rectangular base for the support 47 and also encloses a space in which is mounted the motor 16 and the mechanism for opening and closing the switch. The motor is preferably secured as by screws (not shown) to opposite side walls 68. Also in this space the two condensers 54 and 55 are mounted in a sealed compartment 68a from which three condenser terminals 68b, 68c and 68d are brought out. Three terminals only are required because of the fact that two terminals of the condensers are permanently connected together, as shown in Fig. 1.

Also mounted in this space of the metal wall 68 is the interlock switch constituted by the contact arms 56 and 56a, these contact arms being suitably mounted in an electrically insulating support 68e shown in outline in Fig. 6. This support 68e is secured to the metal wall 68.

The construction of the interlock switch arm 69 is shown clearly in Figs. 5 and 7. It consists of two spring contact arms which are shaped so as to move together at their upper ends and thus in a closed position grasp the stationary contact 69 between them. The opposite ends of the arms 69 are mounted on a pivot 69a. This double contact arm 69 makes the interlock switch free from heavy lateral shocks for the reason that any such shock tending to move one of the two contact arms away from the stationary contact at the same time must tend to move the other contact arm more tightly against the stationary contact.

20 The contact arms are operatively connected to the cross bar 10 by providing a notch 69b in the end of the cross bar through which the contact arms extend. A similar interlock switch 69c is arranged on the other end of the insulating support 47.

In order that the pin 13 will be strong enough to withstand heavy shocks, it is constructed as shown in Fig. 9 as an integral part of the supporting shaft 69d for the gear 14. The pin 13 and the shaft 69d are machined from a single solid piece of hardened steel material. With this construction any shocks applied to the pin 13 are not transmitted to the gear 14 but are taken up by the bearing shaft 69d. This construction makes possible tremendous strength by means of relatively small parts. The gear 14 may be cast on the hub portion to which the pin 13 and shaft 69d are secured, or it may be pressed on the hub.

While we have shown a particular embodiment 40 of our invention, it will be understood, of course, that we do not wish to be limited thereto since many modifications may be made, and we therefore contemplate by the appended claims to cover any such modifications as fall within the true 45 spirit and scope of our invention.

What we claim as new and desire to secure by Letters Patent of the United States is:

1. An electric switch comprising a pair of stationary contacts arranged with one contact substantially above the other contact, a bridging contact member, means supporting said bridging contact member in an upright position for movement into engagement with said stationary contacts, an operating rod substantially rigidly secured at one end to said supporting means, crank means connected to the other end of said rod to operate said contact member, said crank means having its plane of movement substantially parallel with the plane of movement of said contact member so that said crank tilts said supporting means to disengage said contact member from said upper stationary contact before said lower stationary contact is disengaged.
- 50 2. An electric switch comprising a pair of stationary contacts arranged with one contact substantially above the other contact, a bridging contact member, means supporting said bridging contact member in an upright position for movement into engagement with said stationary contacts, an operating rod substantially rigidly secured at one end to said supporting means, crank means connected to the other end of said rod to operate said contact member, said crank means having its plane of movement substantially parallel with the plane of movement of said contact member so that said crank tilts said supporting means to disengage said contact member from said upper stationary contact before said lower stationary contact is disengaged.
- 55 3. An electric switch comprising a pair of stationary contacts arranged with one contact substantially above the other contact, a bridging contact member, means supporting said bridging contact member in an upright position for movement into engagement with said stationary contacts, an operating rod substantially rigidly secured at one end to said supporting means, crank means connected to the other end of said rod to operate said contact member, said crank means having its plane of movement substantially parallel with the plane of movement of said contact member so that said crank tilts said supporting means to disengage said contact member from said upper stationary contact before said lower stationary contact is disengaged.
- 60 4. An electric switch comprising a pair of stationary contacts arranged with one contact substantially above the other contact, a bridging contact member, means supporting said bridging contact member in an upright position for movement into engagement with said stationary contacts, an operating rod substantially rigidly secured at one end to said supporting means, crank means connected to the other end of said rod to operate said contact member, said crank means having its plane of movement substantially parallel with the plane of movement of said contact member so that said crank tilts said supporting means to disengage said contact member from said upper stationary contact before said lower stationary contact is disengaged.
- 65 5. An electric switch comprising a pair of stationary contacts arranged with one contact substantially above the other contact, a bridging contact member, means supporting said bridging contact member in an upright position for movement into engagement with said stationary contacts, an operating rod substantially rigidly secured at one end to said supporting means, crank means connected to the other end of said rod to operate said contact member, said crank means having its plane of movement substantially parallel with the plane of movement of said contact member so that said crank tilts said supporting means to disengage said contact member from said upper stationary contact before said lower stationary contact is disengaged.
- 70 6. An electric switch comprising a pair of stationary contacts arranged with one contact substantially above the other contact, a bridging contact member, means supporting said bridging contact member in an upright position for movement into engagement with said stationary contacts, an operating rod substantially rigidly secured at one end to said supporting means, crank means connected to the other end of said rod to operate said contact member, said crank means having its plane of movement substantially parallel with the plane of movement of said contact member so that said crank tilts said supporting means to disengage said contact member from said upper stationary contact before said lower stationary contact is disengaged.
- 75 7. An electric switch comprising a pair of stationary contacts arranged with one contact substantially above the other contact, a bridging contact member, means supporting said bridging contact member in an upright position for movement into engagement with said stationary contacts, an operating rod substantially rigidly secured at one end to said supporting means, crank means connected to the other end of said rod to operate said contact member, said crank means having its plane of movement substantially parallel with the plane of movement of said contact member so that said crank tilts said supporting means to disengage said contact member from said upper stationary contact before said lower stationary contact is disengaged.

2. An electric switch comprising a plurality of pairs of stationary contacts arranged with one contact substantially above the other contact, a bridging contact member, means supporting said bridging contact member in an upright position for movement into engagement with said stationary contacts, an operating rod substantially rigidly secured at one end to said supporting means, crank means connected to the other end of said rod to operate said contact member, said crank means having its plane of movement substantially parallel with the plane of movement of said contact member so that said crank tilts said supporting means to disengage said contact member from said upper stationary contact before said lower stationary contact is disengaged.
- 75 3. An electric switch comprising a plurality of pairs of stationary contacts arranged with one contact substantially above the other contact, a bridging contact member, means supporting said bridging contact member in an upright position for movement into engagement with said stationary contacts, an operating rod substantially rigidly secured at one end to said supporting means, crank means connected to the other end of said rod to operate said contact member, said crank means having its plane of movement substantially parallel with the plane of movement of said contact member so that said crank tilts said supporting means to disengage said contact member from said upper stationary contact before said lower stationary contact is disengaged.

contact of each pair substantially above the other contact, a plurality of bridging contact members, a cross bar supporting said bridging contact members in upright positions for movement of said contact members in substantially parallel planes into engagement with said pairs of stationary contacts, an operating rod substantially rigidly secured at one end to said cross bar, a crank for operating said rod having a plane of movement substantially parallel with the planes of movement of said contact members and movable from one dead center position to another to move said cross bar between circuit open and circuit closed positions, said crank tilting said cross bar so as to disengage said contact members from said upper stationary contacts before said lower stationary contacts are disengaged, electric driving means connected to operate said crank when said driving means is energized to move said cross bar from said open circuit to said closed circuit position, and a spring connected to said crank so as to be wound up when said cross bar is moved to said closed circuit position, said spring operating when said driving means is deenergized to turn said crank to an open circuit position.

3. An electric switch comprising a support, a stationary contact on said support, a movable contact, an operating member for said movable contact mounted for slidable movement, a crank, a rod connecting said crank to said operating member to move said operating member between closed and open circuit positions upon rotation of said crank, said crank being in a substantially dead center position when said operating member is in each of said positions, electric means for rotating said crank between said dead center positions when said electric means is energized, means for stopping said crank at each of said dead center positions, energy storing means connected to said operating member for moving said member upon deenergization of said electric means to its open position at a predetermined substantially uniform low speed at which alternating current arcing is minimized, and manual means for releasing said operating member from said rod and for thereafter moving said operating member with relation to said rod and lock-

ing said operating member to said support in one of said positions.

4. An electric switch comprising a support, a stationary contact on said support, a movable contact, an operating member for said movable contact, a crank, a driving connection between said crank and said operating member for moving said operating member between closed and open circuit positions upon rotation of said crank, said crank being in a substantially dead center position when said operating member is in each of said positions, electric means for turning said crank to one of said dead center positions when said electric means is energized, means for stopping said crank in each of said dead center positions, energy storing means connected to said crank for turning said crank to said other dead center position upon deenergization of said electric means, and means for releasing said operating member from said crank and for locking said operating member to said support in one of said positions.

5. An electric switch comprising at least two stationary contacts, a bridging contact member, means supporting said bridging contact member for movement between two positions to bring opposite ends of said contact member into engaged and disengaged relation with said stationary contacts, an operating rod substantially rigidly secured at one end to said supporting means, crank means connected to the other end of said rod for operating said contact member, said crank means having its plane of movement substantially parallel with the plane of movement of said contact member so that said crank means tilts said contact member through said operating rod thereby to disengage one end of said contact member from one of said stationary contacts before the other end of said contact member is disengaged from the other of said stationary contacts, and means for driving said crank means to move said contact member between engaged and disengaged positions with respect to said stationary contact.
